RAYMOND T. CLOUD, OF CHICAGO, ILLINOIS

MAGNETIC PICKUP

Application filed December 4, 1930. Serial No. 499,899.

These improvements relate to magnetic pickups, namely devices for translating varying mechanical vibrations into correspondingly varying electrical impulses. Such a device used with a phonograph disc modulates a current in accordance with the variations in the sound track.

The object of this invention is to produce better results through the avoidance of variations extraneous to those desired to be reproduced.

In the accompanying drawings Figure 1 is a top view of a magnetic pickup in accordance with the present invention;

Fig. 2 is a side elevation of the same;

Fig. 3 is an enlarged fragmentary sectional view on the line 3—3 of either Fig. 1 or Fig. 2;

Fig. 4 is a bottom view of the armature with the torsion rod secured thereto; and

Fig. 5 is a side view of the armature showing further how the torsion rod is secured thereto.

Nearly all of the construction details shown in the drawings are old and well-known. That is to say, it is old to provide a base as 10 carrying the permanent magnet 11, the two electro-magnet "voice" coils 12 and 13 having the poles 14 and 15 respectively, the oscillatory armature 16 having a clamping member 17 for the needle or stylus 18, with a torsion rod 20 secured midway between the ends of the armature and transversely thereof, as by crimping metal parts 21 tightly upon the rod 20, with clamping means as 22 and 23 held by screws 24 upon the frame 25 for holding the ends of the torsion rod 20 tightly upon the frame.

The armature 16 is thus, according to old practice, mounted intermediate its end to oscillate in front of the magnet poles 14 and 15 and against the torsional resistance developed in the straight, elongated, slender, spring steel rod or wire 20, which is held rigidly to the armature from side to side thereof and also rigidly at its end portions to relatively fixed supporting means. The oscillations are in parallel planes at right angles to the axis of the torsion rod and in directions toward and from the magnet poles 14

and 15, one end portion of the armature moving toward one pole while the opposite end portion moves away from the other pole, and vice versa.

This rocking or oscillatory movement of the armature is caused by the stylus 18 traveling in the sound track of the record (not shown). The armature is therefore mechanically oscillated in the fields of the poles 14 and 15 against the torsion of rod 20.

In an effort to discover the cause of certain undesirable results in the reproduction I found that since this torsion rod is quite slender and the armature is carried (in the older practice) only by the torsion rod supported at its ends portions, and at places remote from the armature (necessary to provide the desired torsion) the armature has motions in practice which are not purely oscillatory on the true axis of the torsion rod. I found further that these extraneous motions of the armature have a decidedly deleterious effect upon the results.

These oscillatory movements are exceedingly slight. The whole theory of the instrument is based on slight and almost immeasurable variations in the armature movements.

These objections are overcome by supporting the torsion rod intermediate its end portions and the armature. The best results are obtained when the supporting means are positioned as closely as possible to the armature itself. I prefer also to support the torsion rod throughout its length between the armature and the places respectively where the ends of the rod are made fixed. This preferred construction contemplates that while under torsion the rod may have a tendency to bend slightly out of its true axis.

Turning to Fig. 2 it will be observed that I have carried frame 25 upward at 30 and 31 to provide a pair of oppositely extending elongated rests or supporting elements. They may be separate elements but are conveniently a part of that frame 25. These rest or supporting elements 30 and 31 extend inwardly to the armature 16. They terminate at 30a and 31a respectively at the side edges 16a and 16b of the armature, and they may

be flared away slightly as shown to avoid friction with the armature while coming almost into contact with these armature sides. Between the ends 30a and 30b the frame 25 is recessed to accommodate the armature for free movement.

In the top surface of each of these supports 30 and 31 I provide an elongated straight groove or recess marked 33 on one side and 34 on the other, and which may conveniently have a depth of say half the diameter of the cylindrical wire or torsion rod 20. The lateral extensions of the torsion rod rest fairly snugly in these grooves 33 and 34. The 15 grooves extend under the clamping elements 22 and 23 so that when these clamps are tightened down the torsion rod is clamped tightly at its opposite ends and lies perfectly straight in the grooves or recesses 33 and 34.

According to this construction the rod as 20 may develop all of its torsional qualities without inhibition by the recess walls, while these walls provide that such influences as the 25 magnetic attraction, or the dead weight or momentum of the armature and its associated parts, or the mechanical movement of these parts by certain irregularities in the sound track of the record, shall not severally or collectively move the armature out of its true 30 axial position. The result therefore is that the reproduction is not influenced by the extraneous conditions pointed out, but is in accordance with armature movements caused 35 by variations in the sound track alone.

I contemplate as being included in these improvements all such changes, variations and departures from what is thus specifically illustrated and described as fall within the 40 scope of the appended claims.

I claim:

1. In a magnetic pickup of the character described having a magnet, an armature associated therewith and adapted to be oscillated mechanically, and a substantially long, slender and straight torsion rod carried by the armature and extending therefrom substantially at right angles to the plane defining the opposite directions of armature oscillation, with means materially spaced from the armature for fixedly holding the torsion rod to develop torsion therein when the armature is oscillated, the combination therewith of means for supporting the torsion rod adjacent to the armature to maintain the rod substantially straight and to main the armature with a substantially constant axis of oscillation under normal conditions of operation.

2. The combination of claim 1 hereof in which said rod-supporting means include a supporting element having an elongated straight recess therein, the rod resting in said recess.

3. The combination of claim 1 hereof in

which said rod-supporting means include a part having a bearing for the rod substantially on the true axis of the rod, said bearing being closely adjacent to the armature.

4. The combination of claim 1 hereof in which said torsion rod extends laterally of the armature in opposite directions and said supporting means are partly on one side of the armature and partly on the other side thereof in the directions of the rod extensions.

5. The combination of claim 1 hereof in which there is a frame part of the device and said supporting means are integral with said frame part and there is an elongated recess in said frame part and in which recess said rod rests.

6. In a magnetic pickup of the character described having a magnet, an armature associated therewith and adapted to be oscillated mechanically, and an elongated torsion member carried by the armature and extending therefrom substantially at right angles to the plane defining the opposite directions of armature oscillation, with means materially spaced from the armature for fixedly holding the torsion member to develop torsion therein when the armature is oscillated, the combination therewith of means for supporting the torsion member adjacent to the armature to maintain the torsion member on a substantially straight axis and to maintain the armature with a substantially constant axis of oscillation under normal conditions of operation.
